(57) CLAIM

The ornamental design for a locking unit of information storage media case, as shown and described.

DESCRIPTION

FIG. 1 is a perspective view of the locking unit of information storage media case showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged front elevation view thereof; and,

FIG. 9 is an enlarged perspective view thereof.

The broken line showing of the information storage media case is for illustrative purposes only and forms no part of the claimed design.
